COMBINED PROPELLING AND STEERING
MECHANISM FOR BOATS

Delmer F. Sherman, New Plymouth, Idaho

Application August 15, 1950, Serial No. 179,517

3 Claims. (Cl. 115—50)

1

My invention relates to improvements in water craft propelling means of the paddle wheel type which is also used for steering the boat or vessel so that the usual rudder is not needed; and hence the mechanism might be termed a directional power rudder.

One object of the invention is to provide a driving and steering mechanism of the above indicated character in the form of one compact unit which may be readily mounted over an opening in the bottom of a vessel so that the only protruding parts will be portions of the blades of the paddle wheel or wheels.

Another object of the invention is to provide a unit of this character which when mounted adjacent to the center of the vessel—which is where the power plant of the larger vessels are located—will eliminate the usual long drive shaft.

Another object is to provide a combined propelling and steering unit which will make the ship or water craft highly maneuverable since it may be quickly adjusted to drive the ship sideways or in a rearward direction without a mechanism to reverse the direction of rotation of the drive or power shaft.

A further object is to provide an improved paddle wheel structure and means for driving it and mounting it for rotary adjustment about a vertical axis for steering.

With the above and other objects and advantages in view, as will hereinafter appear, the invention resides in the novel combinations and arrangements of parts and in the novel features of construction described and claimed in the following specification, and shown in the accompanying drawings, in which:

Fig. 1 is a vertical sectional view through the bottom of a boat or ship showing the improved propelling and steering unit in side elevation.

Fig. 2 is a vertical section taken on line 2—2 of Fig. 1.

Fig. 3 is a view similar to Fig. 1 showing the gear casings in elevation and the paddle wheel shaft turned through a 90° arc;

Fig. 4 is a bottom plan view of the rotatable semi-spherical casing which houses the paddle wheel;

Fig. 5 is a side elevation of the element shown in Fig. 4;

Fig. 6 is a horizontal section on line 6—6 of Fig. 2;

Figs. 7 and 8 are inner face views of the two sections of the casing for the upper pair of bevel gears which are included in the power drive for the paddle wheel; and

2

Figs. 9 and 10 are inner face views of the two sections of the casing for the lower pair of bevel gears which are included in the power drive for the paddle wheel.

Referring more in detail to the drawings the letter B denotes a portion of the bottom of a boat, ship or other water craft and the numeral 11 denotes as a whole my improved combination propelling and steering unit which is positioned over a circular opening in the bottom B, as seen in Fig. 2. The unit comprises a stationary outer casing section 11 and a rotatable inner casing section 12, these casing sections being preferably semi-spherical and having their open lower ends over the opening in the boat bottom. The outer section 11 includes a flat attaching ring 13 to rest against the inner or outer face of the bottom B with a suitable packing ring interposed. The ring may be secured by an annular series of bolts 14 or similar fastenings passed through apertures adjacent the outer edge of the ring. The casing section 11 may be detachably secured to the ring by an annular series of screws or other fastenings 15 passed through openings in a circular outwardly projecting flange 16 formed around the bottom edge of the section 11, a suitable packing ring being interposed between the flange and ring. The flange 16 is seated on the ring in spaced relation to the inner edge of the ring so as to provide an inwardly extending annular bearing flange 17 on which the bottom of the inner casing section 12 is supported. The bottom edge of the section 12 is widened and formed with an annular raceway for an annular row of anti-friction bearing balls 18 which also run in a similar groove or raceway formed in the top of the supporting flange 17 so the inner section may rotate freely. Forming a part of the rotary mounting of the inner section is a tubular bearing 19 projecting upwardly from the center of the top of the section 11 for the reception of a cylindrical sleeve 20 formed at the top of the inner section. The sleeve 20 projects above the tube or boss 19 and connected to its upper end is a suitable steering mechanism to rotate it, as presently described.

Formed at diametrically opposite points in the thickened lower portion of the rotatable section 12 are bearing openings 21 for the ends of a shaft 22 for a paddle wheel or wheels. As shown two horizontally spaced paddle wheels 23 are fixed to the shaft. Each wheel has a tubular hub 24 keyed or otherwise fastened on the shaft, and a plurality of flat radially projecting blades with beveled outer ends. The paddle blades rotate in the inner section and through the opening into

bottom of the boat to propel it. The paddle wheel shaft has suitably fixed to it adjacent its center a bevel gear 26 which meshes with a similar gear or pinion 27 fixed to the lower end of a power or drive shaft 28. The latter extends vertically upward through and is rotatable in the sleeve 20, its upper end being suitably driven from any power source. Enclosing these gears is a two section gear housing which is supported on the two shafts. One section 29 of the gear casing encloses the gear 26 and a half of gear 27 while the section 30 is in the nature of a cover plate for the main section 29 and has a chambered part 31 to enclose the other half of gear 27. The two sections of the gear casing are united in a plane extending through the longitudinal axis of the drive shaft 28, as will be understood on reference to Figs. 2, 9 and 10, the two sections being fastened together by screws or the like.

As seen in Fig. 2 the upper end of shaft 28 has fixed to it a bevel gear 32 which meshes with a similar gear 33 fixed to a power or propelling shaft 34. The latter may extend in any radial direction from shaft 28 and may be driven from any form of motor or engine. These gears are enclosed in a two section casing similar to the sections 29, 30. The main section 34, shown in Fig. 8, encloses the gear 32 and half of gear 33 while the cover section 35, shown in Fig. 7, encloses the other half of gear 33.

Fig. 2 also shows one way in which the sleeve 20 may be rotated to cause the paddle wheels to steer the boat. A bevel gear 36 has its hub pinned or otherwise secured to the upper end of the sleeve 20, and it meshes with a similar gear 37 fixed to a steering shaft 38. The latter may extend in any radial direction from the axis of shaft 28 and may be turned by any desired steering mechanism. The gears 36 and 37 are enclosed in a two section casing similar to the previously described gear casings or housings. As shown the main section 39 encloses the gear 36 and half of gear 37 while the cover section 40 encloses the other half of gear 37. The gear casing sections have projecting bosses through which the shafts extend, and the boss 41 on the section 39 may rest on or be removably secured to the upper end of the bearing 19. As shown in Fig. 2 the section 34 may rest on the section 40 but it will be understood that means not shown may be provided for bracing or supporting the gear housings.

It is believed the operation of the mechanism will be apparent from the foregoing detailed description. When the shaft 34 is driven the paddle wheels will be rotated to propel the boat, and its direction of movement will depend upon position of the paddle wheel shaft 22 relative to the longitudinal axis of the boat. By turning the steering shaft 34 the inner section 12 may be rotated to cause the paddle wheels to move the boat in any direction forward, sideways or backward.

From the foregoing, taken in connection with the accompanying drawings, it will be seen that novel and advantageous provisions have been made for carrying out the objects of the invention, and while preferences have been disclosed, attention is invited to the possibility of making

variations within the scope of the invention as claimed.

I claim:

1. A combined propelling and steering mechanism for mounting over a circular opening in the bottom of a water craft comprising outer and inner casing members having open circular lower ends the outer member being stationary and having attaching means around its bottom, said outer member also having at the center of its top an upwardly projecting tubular bearing, means mounting said inner member for rotation in said outer member, said mounting means including an annular bearing around the bottom of said inner member and an upwardly projecting cylindrical sleeve fixed to the center of the top of said inner member and extending through and rotatable in said tubular bearing, a rotary shaft mounted diametrically across the lower portion of said inner member, a paddle wheel on said shaft and having its blades movable through the open lower end of said inner member, a vertical power shaft extending through and rotatable in said sleeve, gearing connecting said shafts for rotating said paddle wheel, and steering means connected to the upper end of said sleeve to rotate said inner member.

2. The structure of claim 1 in which said gearing is located adjacent the center of said first mentioned shaft and said paddle wheel comprises two horizontally spaced sections positioned on opposite sides of said gearing.

3. A combined propelling and steering mechanism for mounting over a circular opening in the bottom of a water craft comprising a flat attaching ring, an outer stationary, semi-spherical casing section having its open bottom removably secured on the top of said ring with its bottom edge spaced from the inner edge of said ring to provide an inwardly extending annular bearing flange, said casing section having at the center of its top an upwardly projecting tubular bearing, an inner, rotary, semi-spherical casing section disposed within said outer casing section and having its open bottom edge rotatably supported on said bearing flange, said inner casing section having at the center of its top a cylindrical sleeve extending through and rotatable in said tubular bearing, said inner casing section also having diametrically arranged shaft bearings adjacent its bottom edge, a shaft having its ends rotatable in said shaft bearings, two horizontally spaced paddle wheels having their hubs fixed to said shaft, the blades of said wheels have beveled ends rotatable in said inner casing section and through its open bottom, a vertical drive shaft extending through and rotatable in said sleeve, meshing beveled gears fixed to said shafts and disposed between said paddle wheels, a sectional casing enclosing said gears and supported by said shafts, means at the upper end of said drive shaft for rotating it to drive said paddle wheels, and means at the upper end of said sleeve for turning it to rotate said inner casing section.
